UNITED STATES PATENT OFFICE.

WILLIAM F. HAACK, OF OAK PARK, ILLINOIS.

LEAD PENCIL.

Application filed February 23, 1924. Serial No. 694,550.

This invention relates to lead pencils of the magazine type, which contain a central chamber in which the working lead is held and through which it is advanced by a plunger or pusher as the point of the lead wears away.

A magazine lead pencil of the type above outlined is disclosed in Letters Patent No. 1,469,786, granted to me October 9, 1923. In the aforesaid Letters Patent the working lead is guarded at its upper or inner end against lateral displacement from the lower end of the plunger by means of a laterally offset depending finger or nib on the lower end of the plunger which overlies one side of the upper end portion of the lead and travels in the longitudinal entrance channel to the working chamber through which the lead is introduced. While this feature of my aforesaid patent is in the main satisfactory, yet I have found that occasionally, and especially where the upper end of the lead is not perfectly square, the lower end of the plunger will sometimes get out of register with the lead, crowding down one side of the latter, and thus failing to properly perform its function of advancing the lead through the point or tip of the pencil. Again, if the plunger is retracted before the working lead is sufficiently advanced in the point, the upper end of the lead may swing sidewise out of register with the lower end of the plunger.

The main object of the present invention, which is in the nature of an improvement upon the lead-advancing means of my aforesaid patent, is to provide a centering and positive holding device for the upper end of the working lead carried on the lower end of the plunger and serving to prevent any possibility of the lead at any time getting out of register with the plunger. Another object of the invention is to provide a lead-guiding and centering device of the character above-mentioned that shall be yieldably attached to the lower end of the plunger, so that, when said guiding and centering device strikes the bottom of the working chamber, the lower end of the plunger may follow through the same and continue to feed the fragment of the lead through the tip of the pencil and thereby create in the lower end of the working chamber a well or pocket which, when a new lead is introduced into the working chamber, serves to accurately center the

lower end of the new lead. Still another object is to provide a lead gripping device on the lower end of the plunger, by which a partly used lead may be retracted, released, and returned to the magazine, and another lead of a different color or quality substituted therefor.

Other objects and attendant advantages of the invention will be apparent to persons skilled in this art from the following description, taken in connection with the accompanying drawing in which I have illustrated a practical and preferred embodiment of the invention, and wherein—

Fig. 1 is an elevation, partly in axial section, of my improved magazine lead pencil, showing the plunger in a position wherein the lead-guiding and centering sleeve on its lower end has struck the bottom of the working chamber;

Fig. 2 is a similar view of the lower portion of Fig. 1, showing a further advanced position of the plunger wherein its lower end has projected through and beyond the lower end of the lead-guiding and centering sleeve;

Fig. 3 is a view similar to Fig. 4, showing the plunger and lead-guiding and centering sleeve partially retracted but in the same relative positions to each other as in Fig. 2;

Fig. 4 is a view similar to Figs. 2 and 3, showing the plunger fully retracted and its lower end relocked to the lead-guiding and centering sleeve, and also showing a new lead entering the working chamber;

Fig. 5 is a view similar to Figs. 2, 3 and 4, showing the new lead fully seated in the working chamber and the plunger and sleeve fully engaged with the upper end of the new lead;

Fig. 6 is a detail elevation, broken out between its ends, of the plunger;

Fig. 7 is a fragmentary detail of the lower end portion of the plunger as viewed from the left of Fig. 6;

Fig. 8 is a side elevation of the lead-guiding and centering sleeve;

Fig. 9 is an edge elevation of the lead-guiding and centering sleeve as viewed from the left of Fig. 8;

Fig. 10 is a top plan view of Fig. 8;

Fig. 11 is an enlarged cross-section on the line 11—11 of Fig. 5;

Fig. 12 is an enlarged cross-section on the line 12—12 of Fig. 5; and

Fig. 13 is a cross-section through the

shell and magazine on the line 13—13 of Fig. 1.

Referring to the drawing, 15 designates the cylindrical body or shell of the pencil, which is made of any suitable diaphanous or translucent material which will render the interior parts visible through the same. Within approximately the upper half of the shell 15 is mounted a stationary compartmental magazine 16, which may be conveniently formed by sheet-metal bent into the corrugated cylindrical form illustrated in Fig. 13, each of the longitudinal corrugations constituting a chamber to hold a re-
10 serve lead L. The magazine 16 fits the shell 15 sufficiently tightly to be held stationary relatively thereto, and at its lower end the magazine registers with the upper squared end of the shank or stem portion 17' of a
15 tapered tip or point member 17. The shank 17' is turned down relatively to the diameter of the upper end of the tip 17, thereby forming an annular shoulder 18 against which the lower end of the trans-
20 lucent shell 15 abuts so as to form a flush joint with the external surface of the tip.

As best shown in Figs. 11 and 12, the shank 17' and major portion of the tip 17 are formed with a central circular working chamber 19 and a radial slot 20 leads into said working chamber through the circumference of the shank. The lower portion of the tip is formed with a central axial bore 21 of reduced diameter relatively to
25 the working chamber 19 and of such a size as to fit the leads with sufficient freedom to permit the leads to be pushed therethrough by the plunger, but with sufficient snugness and friction to hold the leads steady when
30 the pencil is in use and against falling out. This construction provides an annular lower end wall 19' for the working chamber 19.

22 designates a plunger or pusher in the form of a rod equipped at its upper end with
45 a short spiral 23 that co-operates with a rotatable tube 24 formed with an internal spiral or screw-thread fitting the spiral 23 of the plunger. The upper end of the spiral tube 24 is tapered and squared to fit a cor-
50 respondingly shaped socket in the lower end of a plug 25 that enters and fits the upper end of the shell 15. This plug 25 has a circular flange 26 that abuts against the upper end of the shell and it also carries a cup
55 27 constituting a holder for an eraser 28. Snugly fitting the reduced upper end of the shell 15 is a sleeve 29 formed with an internal flange or lip 30 that overhangs the flange 26 and locks the plug 25 in place. Covering
60 the cup 27 and eraser 28 is a cap 31 that has a tongue and groove engagement 32 with the cup 27, so that, by turning the cap 31 the spiral tube 24 is rotated to advance or
65 retract the plunger rod. To use the eraser, the cap 31 alone is removed. To reload the

magazine, the cap 31 and sleeve 29 are first removed, whereupon the plug 25 can be lifted out, without the necessity of withdrawing the spiral tube 24. The lower end of the spiral tube 24 forms an annular upper end wall 19' for the working chamber
70 19.

Describing now those features wherein my present improvement mainly resides, the plunger rod 22 is formed a slight distance 75 above its lower end with an integral thin flat web-like portion 33 that is extended laterally beyond one side of the rod to form a lug 34 (Figs. 6, 7 and 11). The web 33 and lug 34 may be formed by mashing the 80 rod, which also forms upper and lower cam inclines 35 and 36 at the junctions of the web with sections of the rod above and below the web. Encircling the lower end of the plunger rod is a spring metal sleeve 85 shown in isolated detail in Figs. 8, 9 and 10, and comprising a pair of opposed approximately semi-circular sleeve sections 37, two opposed edges of which are spaced by a slot 38, while the other opposed edges are 90 integrally joined by a U-shaped spring connector or rib 39, which, as shown in Fig. 11, lies in the groove 20 and itself receives the lug 34 on the plunger rod, whereby the latter and the sleeve are locked against rotation as they are fed up and down. The opposed sections 37 embrace and somewhat loosely fit the lower end portion of the plunger rod, normally extending some distance below the latter; and to yieldably lock 100 this sleeve member to the plunger rod, the sections 37 thereof are formed with a pair of opposed indentations or internal locking lugs 40 that are normally engaged on opposite sides of the reduced portion or web 105 33 of the plunger rod. This lead-guiding and centering sleeve, when thus yieldably locked on the plunger rod, as shown in the sectional view Fig. 11, projects for about 110 half its length below the lower end of the plunger rod; and this projecting portion of the sleeve, after a lead has been entered into the working chamber, telescopes over and lightly grips the upper end of the lead, as clearly shown in Fig. 5, and thus prevents 115 the lead and plunger from getting out of register through lateral displacement of the lead out of the path of the plunger, and likewise makes impossible the jamming of the lower end of the plunger down past 120 one side of the lead which, as hereinabove stated, sometimes occurs when the upper end of the lead and the lower end of the plunger are not perfectly flat or square.

In the practical use of the pencil, the 125 magazines having been loaded, the first lead is introduced to the working chamber by turning the tip 17 and its shank 17' relatively to the shell to bring the upper end of the slot 20 into register with one of the 130

lead compartments of the magazine, whereupon the lead in the said compartment drops into the slot 20. The pencil is then tipped to horizontal or approximately horizontal position with the slot 20 uppermost. This causes the lead to drop from the slot 20 into the working chamber 19. By then returning the pencil to vertical position, with its tip end down, the lower end of the lead enters the bore 21 of the tip and is centered thereby. The cap 31 is then turned, thereby feeding the plunger rod downwardly until the lower portion of the lead-guiding and centering sleeve telescopes over and grips the upper end of the lead, as seen in Fig. 5. Thereupon the feed movement is continued until the point of the lead projects below the point of the pencil, whereupon the latter is primed and ready for use. As the point wears away through use, the lead is advanced from time to time by turning the cap 31. When the lead and plunger have advanced to the point illustrated in Fig. 1, wherein the guiding and centering sleeve has struck the lower end wall 19' of the working chamber, the plunger is still further advanced, and the portion of the plunger above the web 33 is thereby forced between the locking lugs 40, which expands the sleeve; but the latter still engages the rod through the friction of the lugs 40 on the sides of the rod as the latter is retracted to open the working chamber for the admission of the next lead, as shown in Fig. 3. As soon as the upper end of the sleeve strikes the lower end of the spiral 24, which forms the upper wall 19^a of the working chamber, a slight further retraction of the plunger causes the locking lugs 40 to slide down the cams 35 and re-engage with the opposite sides of the web 33, thereby re-establishing the yieldably locked engagement of the sleeve with the plunger. The next lead may then be introduced in the manner already described, and so on until the magazine is empty.

A noteworthy advantage which my improved magazine pencil possesses resides in its adaptability for the selective use at any time of leads of different colors or degrees of hardness. Whenever it is desired to change from one lead to another, this may quickly be done by retracting the plunger and lead until the upper end of the yieldable sleeve strikes the lower end of the spiral tube 24, whereupon a slight further backward movement of the plunger will cause the lower cams 36 to expand the sleeve sufficiently to let the lead drop away from the sleeve. The released lead may be returned first to the slot 20 by holding the pencil horizontal and then to an empty magazine compartment by tipping the pencil up side down. By then turning the slot 20 into register with the compartment of the lead

desired to be used, the new lead is introduced to the working chamber in the manner already described; and, on advancing the plunger, the locking lugs 40 first slide down the cams 36 into re-engagement with the 70 web 33 under the transverse spring of the sleeve, whereupon the latter telescopes over and grips the new lead. It will thus be seen that when any lead has once been introduced to working position in the pencil, it does 75 not have to be used up or discarded before another lead can be employed, but may be returned to its compartment for subsequent reuse, and any other lead in the magazine substituted therefor. 80

I claim:

1. In a lead pencil, the combination of a shell, a tip member fitted into one end of said shell and formed with a working chamber having annular end walls, a plunger rod, 85 a transversely elastic sleeve embracing the advance end of said plunger rod and having a portion thereof normally projecting beyond said plunger rod to telescope over and grip the rear end of a lead in said working 90 chamber, and means yieldably connecting said sleeve to said plunger rod for simultaneous endwise movement of said sleeve and rod, said means permitting said rod to move endwise relatively to said sleeve 95 and expand the latter when the ends of said sleeve contact with the end walls of said working chamber.

2. In a lead pencil, the combination of a shell, a tip member fitted into one end of said 100 shell and formed with a working chamber coaxial with said shell and having a lower annular end wall, a plunger rod, a longitudinally split elastic sleeve embracing the advance end of said plunger rod and having 105 a portion thereof normally projecting beyond said plunger rod to telescope over and grip the rear end of a lead in said working chamber, and cooperating devices on said sleeve and plunger rod yieldably connecting said sleeve and rod to each other under the spring action of said elastic sleeve, said 110 cooperating devices permitting said rod to move through said sleeve and simultaneously expand the latter when the lower end of said sleeve contacts with the said lower end wall of said working chamber.

3. In a lead pencil, the combination of a shell, a tip member fitted into one end of said 115 shell and formed with a working chamber coaxial with said shell and having annular end walls, a plunger rod formed with a narrowed web portion rearwardly of its advance end, and a transversely elastic sleeve 120 embracing and projecting beyond the advance end of said rod and formed with a pair of internal protuberances engaged with said narrowed web portion of the rod, whereby said rod is yieldably connected to said 125 sleeve under the spring action of the latter 130

with capacity of endwise movement relatively to said sleeve when the travel of said sleeve is arrested by either end wall of said working chamber.

5. 4. In a lead pencil, the combination of a shell, a tip member fitted into one end of said shell and formed with a working chamber having annular end walls and a radial slot, a plunger rod, a transversely elastic sleeve embracing the advance end of said plunger rod and having a portion thereof normally projecting beyond said plunger rod to telescope over and grip the rear end of a lead in said working chamber, a hollow rib on said sleeve slidably engaged with said slot, a lug on said plunger rod engaged with said hollow rib, and means yieldably connecting said sleeve to said plunger rod for simultaneous endwise movement of said sleeve and rod, said means permitting said rod to move endwise relatively to said sleeve and expand the latter when the ends of said

sleeve contact with the end walls of said working chamber.

5. In a lead pencil, the combination of a shell, a tip member fitted into one end of said shell formed with a working chamber coaxial with said shell, a plunger rod for forcing the lead endwise through said working chamber, a spiral on the outer end of said plunger rod, a rotatable spiral tube in said shell engaged with the spiral of said rod to advance and retract the latter, said spiral tube formed with a transversely polygonal outer end, a plug removably fitting the outer end of said shell and formed with a circular flange and with a socket fitting the polygonal end of said spiral tube, a sleeve embracing said shell and formed with an in-turned flange overlying said circular flange for locking said plug in place, and a removable cap keyed to said plug for turning the latter and said spiral tube.

WILLIAM F. HAACK.
